UNITED STATES PATENT OFFICE.

ROBERT W. HARDIE, OF WEST ENGLEWOOD, NEW JERSEY.

AIR HUMIDIFIER.

REISSUED

1,404,700.

Specification of Letters Patent. Patented Jan. 24, 1922.

Application filed August 10, 1921. Serial No. 491,088.

To all whom it may concern:

Be it known that I, ROBERT W. HARDIE, a citizen of the United States, and a resident of West Englewood, in the county of 5 Bergen and State of New Jersey, have invented new and useful Improvements in Air Humidifiers, of which the following is a specification.

The invention relates to that class of air 10 humidifiers whereby vapor is discharged into an indoor atmosphere to increase the relative humidity thereof, and is in part a division, and in part a continuation, of the invention contained in the application filed 15 by me in the United States Patent Office on the 20th day of August, 1920, Serial Number 404,951.

The invention is designed primarily to 20 provide means for discharging into an indoor atmosphere, vapor in such a condition that it may be readily taken up by said atmosphere and become diffused therein.

Efforts have heretofore been made to increase the relative humidity of an indoor 25 atmosphere by projecting steam or vapor into such an atmosphere, through a head or casing provided with layers of absorbent material of various kinds.

Those efforts have proved unsuccessful 30 for the reason that such material has no well defined apertures or orifices for steam or vapor to pass through, and consequently the vapor condensed on the absorbent material instead of passing therethrough, and saturated 35 said material with the water of condensation.

A secondary vaporization from the outer 40 surface of the absorbent material takes place under such conditions, without any of the original vapor passing through said material, but the revaporization produces no practical humidifying effect whatever.

Such efforts moreover, have proved impractical for the further reason that absorbent 45 material, saturated with water at a high temperature, and exposed to the atmosphere forms a positive incubating bed for injurious bacteria.

Other efforts have been made to provide 50 devices of that character having their interior filled and packed with material more or less absorbent; such as sponge, cotton, gauze, hair and felt.

Such efforts have likewise proved unsuc-

cessful for the reason that the vapor or steam 55 condensed thereon instead of passing therethrough and for the further reason that the filling of the casing with such material leaves no room for the expansion of the steam or vapor within the casing or for 60 the return of the water of condensation from the steam or vapor which is ordinarily produced in devices of that character.

The main object of this invention is to 65 provide a device whereby steam or vapor under initial pressure or impulsive influence may be reduced as nearly as possible to atmospheric conditions without condensation, or revaporization, and discharged noiselessly into an indoor atmosphere in such condition as to be readily absorbed and diffused 70 therein.

A further object or purpose of the invention is to provide means for controlling the 75 quantity of vapor discharged into the atmosphere, so as to regulate, within limits, the relative humidity of such an atmosphere.

The invention further contemplates the idea of providing a device, of the character disclosed, which may be constructed of a 80 single unit or station, adapted to be placed in the basement or hall of a dwelling or other structure, to discharge sufficient vapor to condition the atmosphere of the entire house or structure, or which may be embodied in small units so as to be placed in 85 separate rooms or subdivisions of a house, or other building.

It is of the greatest importance in some 90 classes of buildings and especially in hospitals to be able to produce in some parts of the building, a different relative humidity from that of other parts of the building, and one of the main objects of the invention is to provide means for so doing.

With the foregoing, and other objects in view, hereinafter stated, the invention consists of the construction hereinafter described, and illustrated in the accompanying drawings which show the invention in 100 its preferred forms; but it is to be understood that other modifications thereof may be employed without departing from the general construction and mode of operation herein illustrated and described.

In the drawings, in which similar reference numerals indicate similar parts throughout the several views, Figure 1 is in 105

part a vertical central cross section and in part a segmental side elevation of a device embodying the invention in one of its forms.

Figure 2 is a plan of the device shown in 5 Figure 1.

Figure 3 is a plan of one of the sections or layers of one of the vapor conditioning members, and

Figure 4 is a side elevation, partly broken 10 away showing a vertical central section of the upper portion of a device having a body or casing substantially similar to that shown in Figure 1 with a conditioning member of modified construction.

15 In carrying out the invention a body or casing of any suitable general construction may be used. In the instance shown, a base 1 is provided with an inlet aperture, 2 adapted to be connected with a source of steam or 20 vapor supply, an annular shoulder, 3 and a flange, 4 having a threaded engagement with the lower end of a shell 5.

The top of the casing may be provided with any desired number of discharge apertures 25 6.

When used with means for controlling the outlet of vapor from said casing, the apertures are preferably arranged in a group at one or more portions of said top, leaving the 30 remainder of said top imperforate.

When desired to regulate the discharge of vapor from the casing, a discharge control plate 7 is mounted upon the apertured top of the casing by means of a pivot pin—or 35 stud 8, and thereby adapted to have a rotary movement on said pin or stud. The discharge control plate 7 is provided with an opening or cutaway portion 9 having an area equal or greater than to that occupied 40 by a group of apertures of the top of the casing. The plate 7 is also preferably provided with a depending hand operated flange 10, loosely engaging the upper part of the body of the device, by means of which the 45 plate 7 may be adjusted, so that the opening thereof may be arranged over an imperforate portion of the top of the casing, or expose any desired number of apertures, and thereby control the quantity of vapor passing out 50 of the casing.

Within the casing there is contained a vapor conditioning member, designed to reduce the initial pressure, and retard the passage, of vapor therethrough, so that the vapor when discharged from the apertures of 55 the top of the casing will be as near as possible of atmospheric condition, thereby enabling the vapor to pass out of the device noiselessly, and in a condition to be readily 60 absorbed by the atmosphere without condensing on objects in the immediate vicinity of the device.

When the device is connected with a source of vapor supply, in which there is 65 but little or no initial pressure, or positive

impulsive effect or influence, the conditioning member may consist of a plurality of layers of woven wire mesh material, 11, laid one upon another.

When so arranged parts of adjacent layers 70 of wire mesh will be in contact with each other, and other parts in separated relation, thereby forming spaces between the respective layers communicating with the apertures or mesh of the layers themselves. 75

As the vapor passes through the body of layers, 11 it is combatted by the strands of the material, its direction is turned first in one direction, then in another, which, together with the friction produced by the 80 wire strands of the member, reduces the initial pressure of the vapor, and permits the vapor to pass noiselessly out of the device, and to be readily taken up by, and diffused into the indoor atmosphere. 85

The layers of wire mesh material are preferably supplemented, for ordinary purposes, with one or more perforated plates or disks 12, at the vapor entering end of the 90 conditioning member.

Those plates cause a portion of the vapor within the body of the casing to be divided out of, and separated from, the remainder of the body of vapor and prevent the vapor within the casing from coming in contact, 95 in the first instance, with the entire surface of the layers of wire mesh. The result is that when the vapor passes through the openings in the perforated plates, the vapor has room to expand and spread within the 100 body made up of the layers of mesh material, thereby aiding in reducing the initial pressure of the vapor. The combined spaces and openings within the conditioning body of the member thereby in effect form a secondary vapor expansion chamber. By reducing the number and size of the apertures of the plate 12, the expansion area within the conditioning member is relatively increased. 105

In cases where the device is connected with a source of vapor supply under positive pressure or impulsive effect or influence, the conditioning member may preferably be constructed largely or entirely of the perforated 115 plates 12, as is shown in Figure 4.

In such cases the apertures of the respective plates are placed in alignment, but not necessarily in axial alignment, with each other, forming multiplicity of independent 120 continuous narrow apertures of extended length, which produce a positive and continuous frictional effect on the vapor passing therethrough, and in that way materially reducing the initial pressure or impulsive 125 influence or effect of the vapor. Some of the apertures that extend through the body of the conditioning member may register with the discharge apertures 6 of the casing as shown in Fig. 4. 130

The conditioning member may be secured in place within the casing in any suitable manner, such as by means of a tubular support 13, having its upper end bearing against the outer margin of the conditioning member and forming a supporting shoulder therefor, and its lower end bearing against the shoulder 3 on the base 1.

The lower end of the tubular support is preferably made long enough to extend slightly below the lower end of the casing wall, so that as the wall of the casing is screwed into, or onto the base 1, the tubular support will be pressed upward, thereby pressing the conditioning member firmly against the under surface of the top of the casing, and hold the conditioning member securely in position. The supporting member also performs the function of closing the joint between the outer margin of the conditioning member, and the inner surface of the wall of the casing and prevents any vapor passing between said parts.

In cases where it is not desired to exert an upward pressure on the outer edge of the conditioning member to hold the layers of foraminous material pressed closely together, it is not essential that the shoulder be made adjustable relative to the casing, nor is it essential that it be made independent of the shell of the casing.

To obtain the best results from the use of this invention in cases where the conditioning member is comprised of layers of wire mesh fabric, it is desirable that the conditioning member be placed with its discharge surface close to the interior surface of the casing, adjacent the discharge openings; so that the vapor, as it leaves the conditioning member will pass directly from the conditioning member into the atmosphere to become immediately diffused therein, and not come in contact with any chamber or passageway intermediate the conditioning member and the point where the vapor finally leaves the device, so as to avoid any condensation of the vapor after it leaves the conditioning member.

In order to reduce to substantially atmospheric conditions, steam or vapor having a positive pressure or impulsive influence, it is necessary to make the openings or apertures of the conditioning member quite fine and minute.

In such cases, because of the minuteness of the apertures in the conditioning member, if any water of condensation forms after the vapor passes through the conditioning member, it will not readily pass back through the conditioning member and at the same time permit vapor to pass through the conditioning member in the opposite direction.

The water of condensation in such cases, will remain on the outer surface of the conditioning member, and in a measure seal the

openings thereof, and prevent the free escape of vapor therefrom.

It is important therefore that the vapor pass freely and directly from the discharge surface of the conditioning member into the atmosphere to prevent condensation in or on the device after the vapor has passed through the conditioning member.

The purpose of the apertures 6 of the top of the casing 5 is to enable the vapor discharged from the device to be controlled by means of a discharge control plate 7. Neither those apertures nor the top of the casing form any part of the conditioning member, and in cases where it is not desired to control the discharge of vapor from the conditioning member, the top of the casing with its apertures 6 is not essential and where the conditioning member or the upper part thereof, is comprised of apertured plates 12, as shown in Figure 4, the apertured top of the casing is not essential even when it is desired to control the amount of vapor passing out of the conditioning member.

By placing the conditioning member at the discharge end of the casing the discharged vapor is not only prevented from condensing on the device, but in addition thereto an expansion chamber is provided between the inlet aperture and the conditioning member which permits the vapor entering the casing to expand and lose some of its initial pressure, or impulsive influence.

In addition thereto such an expansion chamber provides for a free return to its source, of the water of condensation, due to the difference in temperature between that of the vapor and of the casing, the outer surface of which is exposed to the indoor atmosphere.

By getting rid of the free particles of water in the expansion chamber, and providing for the unobstructed return of the water of condensation from said chamber and such heavily laden vapor as is too coarse to pass through the conditioning member, only vapor in its most fitting condition passes into the conditioning member.

It is quite important that some means be provided for controlling the discharge of vapor into an indoor atmosphere. At certain times or seasons of the year, as in the spring or fall it is necessary to have some heat, yet the outdoor atmosphere may be unusually moist and the air supplied with a high per cent of humidity.

At such times it is not necessary to supply an indoor atmosphere with the same amount of humidity in proportion to the quantity of heat supplied, as at other times, therefore means should be provided for limiting the quantity of vapor discharged into the atmosphere indoors.

On the other hand, there are times and

seasons when the outside atmosphere is lacking in the average amount of humidity relative to its temperature, and in such case, the discharge of vapor indoors should be 5 regulated or controlled so as to provide a greater discharge of vapor in proportion to the amount of heat supplied, than at other times.

Again in hospitals, and other places it is 10 necessary to provide a percentage of relative humidity in one part of the building different from that in another part of the building.

The means herein disclosed are well 15 adapted to control the indoor humidity as a whole, or by applying a plurality of units in different parts of a building; the different parts may be provided with humidity of the relativity desired.

20 In the constructions shown and described the layers of material comprising the conditioning member are arranged in horizontal planes; that is not however an essential feature of the invention, nor is it essential 25 that the discharge apertures be formed in the top of the casing. Such construction is preferred, however, for by such means the movable plate 7 may be brought directly and closely over any desired number of 30 apertures, thereby positively closing said apertures against the escape of any vapor therefrom; and positively controlling the quantity of vapor passing out of the device, into the atmosphere.

35 It is preferable to make the layers of wire mesh material of a finer and closer mesh at the entering end of the member than at the discharge end, so as to restrict the passage of vapor at the entering portion more than 40 at the discharge portion.

The particular size of the mesh, or of the apertures of the layers of material making the conditioning member and the number of layers used, is not of the essence of the 45 invention.

For most purposes ninety mesh and eight or ten layers of material may be used.

When apertured plates are used the apertures of the plates may be of about one sixtieth of an inch or less in diameter, and layers enough may be used to make the conditioning member of one half an inch or more in thickness:

Instead of providing the inlet end of the

device with an interiorly threaded base, as 55 shown in the drawing, that end may be provided with an exteriorly threaded stem and may extend laterally from the member as in the radiator air valves of ordinary construction, or vertically in line with the axis 60 of the body of the device.

What I claim as new and desire to secure by Letters Patent is:

1. An air humidifying device comprising 65 a casing having an inlet aperture and a plurality of discharge apertures, a vapor conditioning member having a plurality of superimposed layers of foraminous, non-absorbent material within said casing, with its discharge face adjacent to the interior 70 surface of the apertured part of the discharge end of said casing, with apertures of said member communicating directly with the discharge apertures of said casing, and a discharge control plate mounted upon said 75 casing and adapted to expose or cover said discharge apertures.

2. An air humidifying device comprising 80 a casing having an inlet aperture at its lower end, a vapor conditioning member 85 within the casing having a plurality of superimposed layers of non-absorbent material provided with apertures extending from the interior of the casing and exposed at their outer terminals to the atmosphere, 90 and a discharge control plate mounted upon the discharge end of said casing and adapted to expose or cover the apertures of said conditioning member.

3. An air humidifying device comprising 90 a casing having an inlet aperture at its lower end, a vapor conditioning member associated with said casing having a plurality of superimposed apertured plates, the corresponding apertures of the respective 95 plates being in alignment with each other leading from the interior of said casing, and exposed at their outer terminals to the atmosphere, and a pivotally mounted discharge control plate mounted upon the 100 discharge end of said casing and adapted to expose or cover the apertures of said plates.

ROBERT W. HARDIE.
